AUTOMATIC STARTER

Carl N. Boyd, Los Angeles, Calif.

Application September 23, 1932, Serial No. 634,476

3 Claims. (Cl. 290—36)

My invention relates to means for automatically operating starting devices for internal combustion engines, and is of especial utility with the starting motors for automobile engines. My present invention is an improvement on the known type of starter controlling device which utilizes the variations of the electrical characteristics of the generator connected to the engine, and has for its principal object to provide an automatic starting control which will be positive in its operation and will avoid many of the weaknesses inherent in starting devices now employed; and which is of such character that it may be employed with any of the known power plant installations of automotive vehicles without the necessity of careful and expert adjustment, but which in most instances may be installed in the automotive vehicle and will operate in a fully practical condition without adjustment after being installed.

In the extensively used electrical starting controls the rise and fall of the voltage of the generator is employed to control the operation of the electromagnetic starter switch which controls the flow of current from the storage battery of the automobile to the starting motor, it being intended that when the ignition switch of the automobile is turned on, the starter switch will be automatically closed so as to operate the starter, that the rise of the generator voltage to a predetermined value will cause the starter switch to open after operation of the engine has been accomplished by use of the starting motor, and that the voltage of the generator will hold such starter switch open until the motor is for some reason stopped. It is found, however, in these devices that when the automobile engine is being operated at low speed, there will be an intermittent cutting-in of the starting switch while the engine is in operation, a condition not desired and one which is liable to result in breakage of the teeth of the starter gears. Another fault of the electrically controlled starting devices now in common use is that they are rendered inoperative by the failure of the generator or the failure of the generator to be driven, as by the breakage of the fan belt or other belt or chain by which the generator is driven.

It is an object of my invention to provide a starting device which has two automatic controlling means which produce the practically perfect operation found in the use of my new device and which will be evident from the following description.

It is an object of the invention to provide a starting device which for its control has a controlling element operated by partial vacuum existing within the intake manifold of the engine and a cooperating controlling element which functions in response to the change of electrical characteristics of the generator driven by the automobile engine.

It is an object of the invention to provide a device of the above character which will close the electrical circuit to the starting motor coincident with the closing of the ignition switch and will hold such circuit closed until the operation of the engine produces a predetermined condition of partial vacuum within the intake manifold, at which time the circuit to the starting motor is held open until the voltage of the generator drops to substantially zero value, this condition requiring that the engine shall be stopped before the starter control will again automatically actuate to close the starting motor circuit.

It is an object of my invention to provide a device of the character above described having a controlling switch which may be opened by either partial vacuum produced in the intake manifold or by the rise in the voltage of the generator to a predetermined value, both of which switch-opening means are in operation during the normal operation of the internal combustion engine.

A further object of the invention is to provide a device of the above character which is of simple and sturdy construction so as to retain its initial adjustment after it is installed and which under most conditions of installation requires no adjustment after being connected to the power plant of the automotive vehicle.

Further objects and advantages of the invention will be made evident throughout the following part of the specification.

Referring to the drawings, which are for illustrative purposes only,

Fig. 1 is a face view of a simple and preferred embodiment of my invention with the cover plate thereof removed.

Fig. 2 is a cross section on a plane represented by the line 2—2 of Fig. 1, showing the parts in their relative positions during the time the ignition or other manually controlled circuit is open.

Fig. 3 is a cross section similar to Fig. 2 but showing the relative positions of the parts during normal operation of the automobile engine.

Fig. 4 is an electrical diagram showing a preferred manner of connecting the device with a standard type of automobile power plant.

Fig. 5 is a fragmentary diagrammatic view co-

operating with Fig. 4 to show an alternative method of employing the device.

As shown in Figs. 1, 2, and 3, for the support of the mechanism of my device I prefer to employ a casing or box 11 of insulating material, such as bakelite, this casing having a rear or back wall 12, upper and lower outstanding walls 13 and 14, and outstanding side walls 15 and 16, there being lugs 17 with bolt or screw openings 18, as shown in Fig. 1, for use in securing the device in operative position. At one side of the upper wall 13, such as the left side thereof, I mount a solenoid 20 forming part of a starter motor switch 21 including stationary contacts 22 and 23 and a movable contact 24 consisting of a metal disc mounted on the lower reduced end 25 of an armature 26 which projects upwardly into the opening 27 provided by a brass tube 28 on which the solenoid is mounted. The brass tube 28 is secured to a short cylindrical portion 30 which extends downwardly from a metal base 31 secured by means of a screw 32 to the lower face of the wall 13. The contact 22 is of L-shaped form and is secured to the side wall 15 of the casing 11 by means of a heavy screw 33, the outer end 34 of which constitutes a starter circuit terminal and, as shown in Fig. 4, is adapted to be connected to a starting motor 35 by means of a cable 36. The contact 23 consists of a flat plate held against the upper end of a body or lug 37 of insulating material formed on the upper face of the lower wall 14 of the casing 11, a screw 38 passing downwardly through the contact 23 and the lug and having a lower projecting end 40 forming another starter circuit terminal which is adapted to be connected, as shown in Fig. 4, with the service terminal 41 of the automobile battery 42 by means of a cable or conductor 43. The movable contact or disc 24 is mounted on the stem 25 in a slidable and rockable manner and is insulated from the solenoid 20 by use of insulating means 44. A spring 45 normally forces the contact member 24 upwardly toward a shoulder 46 formed at the upper end of the stem 25, the lower end of the spring 45 being retained by a small flange 47 at the lower end of the stem. When the solenoid 20 is energized, the armature 26 is pulled upwardly against the action of a spring 48, thereby bringing the movable contact member 24 into engagement with the stationary contacts 22 and 23, and closing the circuit to the starting motor which is grounded as indicated at 50 in Fig. 4, the current returning to the battery 42 through a grounded conductor 51.

Auxiliary to the solenoid 20 I provide a means 55 for closing the switch 21, consisting of a button 52 which projects through an opening 53 in the lower wall 14 of the casing 11 in a position substantially aligned with the stem 25, so that by forcing upwardly on the button 52, the armature 26 may be raised to bring the contact 24 into engagement with the contacts 22 and 23.

For controlling the energization of the solenoid 20 I provide a switch means 54 including a rocking plate 55 which is fulcrumed at an intermediate point in a notch 56 formed in the outwardly extending flange 57 at the upper end of a plate 58 which is secured to the outer end of a core 60 forming part of a control magnet 61. The lower end of the plate 58 has a tongue 62 which is bent outwardly and then upwardly so as to overlie the lower end of the plate 55. To this tongue 62 a spring 63 is secured in such position that its upper end 64 will force inwardly against the upper end of the plate 55 and cause it to swing toward a position in which

a contact element 65 of silver will engage a contact element 66 mounted in the outer end of a stem 67 forming a part of a vacuum switch element 68.

The stem 67 is slidable in an opening 70 formed in a circular metal body or cover member 71 having a peripheral flange 72 whereby it may be secured by screws 73 to a circular wall 74 which projects outwardly from the rear wall 12 of the casing 11 to provide a vacuum chamber 75. Washers 76 mounted on the inner end of the stem 67 provide a means for connecting the stem 67 to a diaphragm 77, the periphery of which is clamped between the flange 72 of the member 71 and the wall 74 of the chamber 75. The stem 67 is normally urged outwardly toward the position in which it is shown in Fig. 2 by means of a spring 78 which surrounds the stem 67 and has its inner end in engagement with the cover 71 and its outer end in engagement with a collar or washer 80 secured to the outer end of the stem 67. Near the inner end of the stem 67 an indentation is formed by a peripheral groove 81 adapted to be engaged by a ball 82 resting in the lower end of an opening 83 in the cover 71, this ball 82 being resiliently forced toward the stem 67 by means of a spring 84, the outer end of which may be engaged by a countersunk adjustment screw 85 mounted in the upper wall 13 of the casing 11. Communicating with the vacuum chamber 75 is an opening 86 which extends through the upper wall 13 and is fitted with a nipple 87 whereby it may be connected through a metal tube 88 with the intake manifold of the automobile engine. The condition of partial vacuum produced in the intake manifold of the automobile engine is transmitted through the tube 88 to the vacuum chamber 75, with the result that the diaphragm 77 is deflected inwardly as shown in Fig. 3, thereby carrying the contact 66 from engagement with the contact 65 carried by the plate 55.

As shown in Figs. 1 and 4, an ignition switch terminal 90 is mounted in the upper wall 13 and through a lead 91 is connected with the solenoid 20. The solenoid 20 has its lower end connected through a wire 92 with the cover member 71 and is therefore in electrical connection with the contact 66 carried at the outer end of the stem 67. A flexible wire or cable 93 connects the plate 55 with a ground terminal 94 mounted in the lower wall 14 of the casing 11. In the ordinary use of the invention this ground terminal 94 is connected through a jumper 95 with a ground terminal 96 which connects through a wire 97 with the magnet 61. In the side wall 16 of the casing 11, a generator terminal 98 is mounted in a position to connect through a wire 100 with the magnet 61.

The installation and operation of the invention are as follows: The starter motor circuit terminals 34 and 40 are connected to the starter motor 35 and the battery 42 by means of cables 36 and 43, as previously explained; the ignition terminal 90 is connected through a wire 101 with the dead contact 102 of an ignition switch 103; the generator terminal 98 is connected through a wire 104 with the output terminal 105 of a generator 106 which is driven by the automobile engine not shown; and the ground terminal 96 is grounded with the frame of the vehicle through a ground wire 107. In the wiring diagram, Fig. 4, in accordance with standard practice I show a generator cut-out 108 which is 75

connected to the output terminal 105 of the generator 106 and through a wire 110 is connected to an ammeter 111. From the ammeter 111 a conductor 112 is carried to the terminal 41 of the 5 battery 42 or some conductor which is in electrical connection with the terminal 41. The ignition switch 103 is shown connected through a wire 113 with the ammeter 111, and from the contact 102 thereof a wire 114 is carried to the 10 ignition mechanism 115 employed with the engine, such ignition mechanism ordinarily consisting of a coil and distributor. When the ignition switch 103 is in open position as shown in Fig. 4, the contacts 65 and 66 of the control 15 switch 54 are in engagement, with the result that there is a closed electrical path extending from the contact 102 and through the solenoid 20 to the ground 107. Accordingly, closing of the ignition switch 103 results in a flow of electric 20 current from the battery 42 through the solenoid 20 as well as to the ignition equipment 115, so that the energization of the solenoid 20 raises the armature 26 and closes the starting circuit switch 21 to operate the starting motor 35. The 25 engine is thereby turned over and combustion is produced in the cylinders thereof, with the result of rotating the shaft at a speed higher than that at which it is rotated by the starter and at the same time producing in the intake manifold 30 a condition of partial vacuum sufficient to overcome the detent action of the ball 82 in engagement with the groove 81 and pull the diaphragm 77 into the position in which it is shown in Fig. 3, and breaking the circuit of the solenoid 20 by 35 removing the contact 66 from engagement with the contact 65, thus releasing the switch 21 and stopping the starting motor. The speed at which the generator 106 is driven is proportionate to the speed of the engine, and as the speed of rotation of the engine increases, the generator voltage 40 builds up, producing a flow of electrical energy through the conductor 104 and the magnet 61. As soon as the magnetic flux in the magnet 61 reaches a predetermined strength, the 45 lower end of the plate 55 is drawn inwardly against the end of the core 60 of the magnet 61, thereby swinging the contact 65 outwardly from the position, as shown in Fig. 2, in which it may be engaged by the contact 66 to the position in 50 which it is shown in Fig. 3, wherein it cannot be engaged by the contact 66 even though the contact 66 should return to its engagement position as indicated by dotted lines 117, Fig. 3. The magnetic opening of the switch consisting of the 55 contacts 65 and 66 may occur simultaneously with the action of the vacuum control device 68. In the ordinary practice of the invention, however, it does not occur until after the actuation of the vacuum switch element 68 owing to the 60 fact that the gap 118 below the lower end of the plate 55 and the outer end of the core 60 requires a greater magnetic flux than is required to hold the plate 55 in engagement with the core 60 after they have become engaged. Likewise, 65 the plate 55 will be magnetically held in the open position shown in Fig. 3 until the rotation of the generator stops, owing to the very small magnetic flux required to prevent this engagement of the lower end of the plate 55 with the outer end of the core 60. Therefore, the inadvertent or improper release of the vacuum actuated element 68 will not result in actuation of 70 the starting motor for the reason that the contact 66 cannot engage the contact 65 until the 75 magnetic release of the plate 55. In the ordinary

operation of an automotive vehicle, the inadvertent release of the magnetically actuated element does not occur; but should the vehicle be in operation at a low speed, such as three to five miles per hour, and the throttle of the carburetor 5 be suddenly opened, the condition of vacuum within the intake manifold will suddenly drop to substantially zero, and a release of the vacuum actuated element 68 will occur. This, however, does not result in the closing of the starter switch 10 21, for the reason that the closing of the switch contacts 65 and 66 requires that the generator be brought to a dead stop.

A feature of my invention is that it will give a reasonably satisfactory operation through the 15 use of the vacuum actuated controlling means 68, as, in the ordinary driving of an automobile, the above noted drop in the vacuum condition in the intake manifold to substantially zero is 20 rarely produced.

The invention also provides frictional means 25 consisting of the ball 82 for retarding the switch-closing movement of the stem 67 so that there is a slight delay in the outward movement of the stem 67 after the vacuum condition within the 30 vacuum chamber 65 is released.

With the idea in mind of preventing access to the ignition circuit of an automobile, some of the late automobiles have the leads from the ignition switch extended through armored cables, and 35 the terminals to which these are attached are concealed, thus making it difficult to connect my starting control in the manner previously described. For such exigencies my invention provides a means for connecting the device independently of the starting circuit, but in such a manner that it will be operated coincident with the closing of the ignition switch of the automobile. In such instances the jumper 95 is switched over so that it connects the terminal 94 with the 40 terminal 40, as shown by dotted lines 120 in Fig. 4, and the wire 101, instead of being connected to the terminal 102 of the ignition switch, is connected, as indicated in Fig. 5 by dotted lines 121, with a ring 122 which is mounted around the exposed end of the operating body or element 123 of an ignition switch such as shown at 119 and has a portion 124 thereof in a position to be engaged by the end 125 of the part 123 of the ignition switch when, by use of a key 126, the member 123 is released and caused to move into the projecting position indicated by dotted lines 127, thereby grounding the terminal 90 through the metal parts of the ignition switch 119 so that 45 current will flow from the battery 42 through the conductor 43 to the terminal 94 which, as previously described, is in circuit with the solenoid 20, the circuit being completed by the conductor shown in dotted lines 121 which is grounded coincident with the closing operation of the automobile ignition switch. It will be understood that the operation of my invention in conjunction with the ignition switch is only a matter of convenience, for a separate switch may be employed, 50 mounted on the instrument board of the automobile in position to be turned on and off as desired.

Although I have herein shown and described my invention in simple and practical form, it is recognized that certain parts or elements thereof 55 are representative of other parts, elements, or mechanisms which may be used in substantially the same manner to accomplish substantially the same results; therefore, it is to be understood that the invention is not to be limited to the 75

details disclosed herein but is to be accorded the full scope of the following claims.

I claim as my invention:

- 5 1. An automatic starter control for use with a combustion motor having an electric generator and a starter associated therewith, including: a starter circuit for energizing said starter; a magnetic switch in said starter circuit; a control circuit connected to said magnetic switch; a control switch in said control circuit, said switch comprising a pair of contacts; an armature supporting the first of said contacts; magnetic means electrically connected to said generator for moving said armature to carry said first contact away
- 10 15 from the second of said contacts; a member supporting said second contact; means operated by vacuum of the intake manifold of said motor to move said member so as to carry said second contact away from said first contact; and means for

yieldably moving said contacts into engagement.

2. A device as defined in claim 1 in which said member supporting said second contact has a detent means for initially restraining movement of said second contact and abruptly releasing so as to cause a rapid movement of said second contact away from said first contact.

5 3. A device as defined in claim 1 in which said member supporting said second contact has a depression therein, and in which said vacuum operated means comprises a diaphragm, means forming a vacuum chamber adjacent one side of said diaphragm, said diaphragm being connected to said member supporting said second contact, a body engaging said depression in said member, 10 and a spring for forcing said body into said depression.

10 15 CARL N. BOYD
